(57) **CLAIM**

The ornamental design for a diaphragm pump, as shown and described.

DESCRIPTION

FIG. 1 is a front view of a diaphragm pump showing our new design;

FIG. 2 is a back view thereof;

FIG. 3 is a right side view thereof;

FIG. 4 is a left view thereof;

FIG. 5 is a top view thereof;

FIG. 6 is a bottom view thereof;

FIG. 7 is a top perspective view; and,

FIG. 8 is a bottom perspective view.

The broken lines are included for the purpose of illustrating portions of the diaphragm pump that form no part of the claimed design.
